United States Patent Office

Des. 201,740
Patented July 20, 1965

201,740

LUGGAGE CASE

Paul O. Rawson, Jr., Trumbull, Conn., assignor, by mesne assignments, to J. C. Penney Company, Inc., a corporation of Delaware

Filed Nov. 24, 1964, Ser. No. 82,767

Term of patent 14 years

(Cl. D87—2)

FIG. 1

Des. 201,740

PAGE 2

FIG. 2

FIG. 3

FIG. 4

FIG. 5

FIG. 1 is a top perspective view of a luggage case showing my new design;

FIG. 2 is a top plan view thereof;

FIG. 3 is a side elevational view thereof;

FIG. 4 is an end elevational view thereof; and

FIG. 5 is a rear elevational view thereof.

The essential features of my new design are shown in full lines in the drawings.

I claim:

The ornamental design for a luggage case, as shown and described.
